UNITED STATES PATENT OFFICE.

EDGAR J. WOOD, OF ELKLAND, PENNSYLVANIA.

AUTOMATIC TRAIN-STOP.

1,366,233.

Specification of Letters Patent. Patented Jan. 18, 1921.

Application filed November 5, 1920. Serial No. 421,847.

To all whom it may concern:

Be it known that I, EDGAR J. Wood, of Elkland, in the county of Tioga and State of Pennsylvania, have invented certain new

and useful Improvements in Automatic Train-Stops; and I do hereby declare the following to be a full, clear, and exact description of the invention, such as will enable others skilled in the art to which it

10 appertains to make and use the same.

My invention relates to automatic train stops, and the object of the invention is to provide a simple and highly efficient mechanism which will automatically operate the 15 engineer's valve of an air brake system upon engagement between a lever arm of the mechanism and a signaling member of the semaphore type. A further object is the provision of a heating element adjacent the 20 lever arm to prevent freezing of the parts which normally maintain the lever arm in an upright position.

In the drawings, Figure 1 is a view in perspective showing a portion of a locomotive cab with my improved mechanism applied thereto and indicating a semaphore set in position for engagement with the lever arm. Fig. 2 is an enlarged view of my improvement in side elevation, the semaphore arm being shown in section. Fig. 3 is a sectional view on line 3—3, Fig. 2. Fig. 4 is a detail showing a portion of the trip device. Fig. 5 shows a slight modification of the tripping means, and Fig. 6 is a sectional view on line 6—6, Fig. 5.

Referring to the drawings, the cab of an engine is indicated at A and the semaphore arm of known form at B. Mounted on the top of the cab at one side is a housing 1 in which are bearings 2, 3 for a transverse shaft 4, the cranked end 5 of which is connected by a link 6 with a lever 7 pivoted at 8 on a bracket 9 secured to the inside of the cab, a spring 10 tending to normally hold this lever in an approximately horizontal position and in locking engagement with a lip 12 of a weight 13. This weight is fast on a crank shaft 14 having its bearings in ears 15 of a bracket 16 secured to 40 the cab, and the turning movement of the weight is effective through its crank 14 to operate a rod 17 to turn the engineer's valve indicated at C. It is manifest that while I have shown the valve with a horizontally disposed handle valves otherwise positioned 45 may be effectively actuated by simply

changing the connection between the rod 17 and the valve handle. The extent of movement of the weight 13 is controlled by a spring 18.

The shaft 4 has an extension 19 to which is secured an arm 20, the arm being maintained in a normally upright position by a spring catch 21 carried by the arm and extending outwardly therefrom into an aperture 22 of a part of the housing 1. This spring catch is designed to be disengaged from its normal locking position by either of two trip fingers 23 each of which has a pivotal connection with the arm 20 on opposite sides of its center line, a horizontally disposed portion 24 of the finger having a notch 25 which takes in a pin 26 spanning the pronged end of the catch 21. The outer portions of the fingers are disposed upwardly at an angle to the perpendicular in such spaced relation to the arm 20 as to insure engagement of the finger by the semaphore arm sufficiently in advance of contact between the semaphore and the arm 20 to allow the finger to trip the catch thus releasing the arm 20 and permitting it to be rocked by its contact with the semaphore arm and to operate the parts heretofore described for actuating the engineer's valve. 85 It will be seen that two of these trip fingers are required, one effective in forward running of the locomotive and the other in backing, the arm 20 being operable in either direction of movement of the engine. In 90 the event that two locomotives equipped with my improved device are used I arrange for disconnection of the mechanism of one of the engines. This is effectively done by removing cotter pin 30 and disconnecting 95 link 6 and lever 7. After the mechanism heretofore described has been actuated by engagement with the semaphore the parts may be readily and quickly restored to normal position by pulling on one or the other 100 of two cords 31 attached to a cross arm 32 fast on the shaft 4 and at the same time lifting the weight 13 by means of a handle 33 into its proper position with its lip engaged by the arm 7.

In order to avoid any trouble in the operation of the mechanism herein described because of freezing at the point where the spring catch 21 engages the housing I run a steam pipe through the housing, as indicated at 34, the pipe being connected with the steam line of the train supply. This

engagement is effective to keep the housing heated to a freeze preventing degree.

In Fig. 5 I have shown a slightly different arrangement of the means for operating the 5 spring catch which normally holds the arm 20 in upright position. The trip fingers 23^a are each pivotally connected with the arm 20 on opposite sides of its center line, the end of the horizontally disposed portion 24^a having a sector gear 25^a, the gears of the two 10 fingers intermeshing. Each of the fingers is connected with the catch 21^a so as to disengage the catch to permit turning of the arm 20. The connection between each finger 15 and the catch includes a perpendicular rod 26^a having a horizontally disposed portion 27^a, the latter having appropriate connection with the catch 21^a. In the operation of the device, contact with either finger 20 23^a will trip the catch and the formation of the parts is such that both fingers will move, the geared ends insuring this. It will be understood that this functioning of both 25 fingers aids in the easy withdrawal of the catch and prevents any canting of the catch.

In operation, with the mechanism in normal position, engagement between the semaphore B and one of the trip fingers 23 will disengage the spring catch 21 and permit the arm 20 to be rocked by the semaphore, thus turning the shaft 4 and through its cranked connection with the lever 7 turning the latter to disengage the end of the lever and the lip 12 of the weight 13, the latter immediately dropping and through its cranked connection with the rod 17 actuating the engineer's valve. The parts are restored to normal position in the manner before described. The advantages of my 30 invention will be apparent. It will be observed that I have provided a very simple and effective device for applying the air brakes in the event the engineer has failed to observe the signal set against him and that the mechanism entering into the make-up of my device will not readily get out of order or require constant attention. Once 35 set there is no likelihood of the parts being jarred by the momentum of the locomotive into accidental actuation.

I claim as my invention:

1. Mechanism for automatically actuating the air brake system of a railway train through the instrumentality of a signal arm 40 including a housing superposed on the cab of a locomotive, a crank shaft supported in said housing, a lever supported in the cab and having a linked connection with said crank shaft, a weight maintained in upright position by said lever, a valve actuating rod connected with said weight, an arm on said 45 crank shaft, means for locking said arm in upright position, and tripping means carried by said arm for releasing said last mentioned means to permit said arm to rock said

crank shaft and turn said lever to free the weight.

2. Mechanism for automatically actuating the air brake system of a railway train through the instrumentality of a signal arm 70 including a housing superposed on the cab of a locomotive, a crank shaft supported in said housing, a lever supported in the cab and having a linked connection with said crank shaft, a weight supported for turning movement in said cab, said weight being maintained in upright position by said lever, a valve actuating rod connected with said weight, an arm on said crank shaft, means for locking said arm in upright position, and tripping means carried by said arm for releasing said last mentioned means to permit said arm to rock said crank shaft and turn said lever to free the weight. 75

3. Mechanism for automatically actuating the air brake system of a railway train through the instrumentality of a signal arm 80 including a housing superposed on the cab of a locomotive, a crank shaft supported in said housing, a lever supported in the cab and having a linked connection with said crank shaft, a weight maintained in upright position by said lever, a valve actuating rod connected with said weight, an arm on said crank shaft, a spring catch for locking said arm in upright position, and tripping members carried by said arm for releasing said spring catch, said members being operable in the forward or rearward movement of the locomotive, release of said spring catch permitting said arm to rock said crank shaft and turn said lever to free the weight. 90

4. Mechanism for automatically actuating the air brake system of a railway train 95 including a housing superposed on the cab of a locomotive, a crank shaft supported in said housing, a lever supported in the cab and having a linked connection with said crank shaft, a weight maintained in upright position by said lever, a valve actuating rod connected with said weight, an arm on said crank shaft, a spring catch for locking said arm in upright position, trip fingers having a pivotal connection with said arm and adapted to release said spring catch to permit said arm to rock said crank shaft and turn said lever to free the weight and a geared connection between said fingers to effect simultaneous movement of said fingers. 110

5. Mechanism for automatically actuating the air brake system of a railway train 115 including a housing superposed on the cab of a locomotive, a crank shaft supported in said housing, a lever supported in the cab and having a linked connection with said crank shaft, a weight maintained in upright position by said lever, a valve actuating rod connected with said weight, an arm on said 120

- crank shaft, a spring catch for locking said arm in upright position, two trip fingers pivotally connected with said arm and each having an independent connection with said 5 spring catch, a geared connection between said trip fingers for effecting their simultaneous operation in the forward or rearward movement of the locomotive to release said spring catch to permit said arm to rock 10 said crank shaft and turn said lever to free the weight.
6. Mechanism for automatically actuating the air brake system of a railway train through the instrumentality of a signal arm 15 including a housing superposed on the cab of a locomotive, a crank shaft supported in said housing, a lever supported in the cab and having a linked connection with said crank shaft, a weight maintained in upright 20 position by said lever, a valve actuating rod connected with said weight, an arm on said crank shaft, a spring catch for locking said arm in upright position, two trip fingers pivotally connected with said arm and each 25 having an independent connection with said spring catch, said trip fingers being operable in the forward or rearward movement of the locomotive to release said spring catch to permit said arm to rock said crank shaft
- and turn said lever to free the weight, and 30 a heating element for preventing freezing of said spring catch.
7. Mechanism for automatically actuating the air brake system of a railway train through the instrumentality of a signal arm 35 including a housing superposed on the cab of a locomotive, a crank shaft supported in said housing, a lever supported in the cab and having a linked connection with said crank shaft, a weight maintained in upright 40 position by said lever, a valve actuating rod connected with said weight, an arm on said crank shaft, a spring catch for locking said arm in upright position, two trip fingers pivotally connected with said arm and each 45 having an independent connection with said spring catch, said trip fingers being operable in the forward or rearward movement of the locomotive to release said spring catch to permit said arm to rock said crank shaft 50 and turn said lever to free the weight, and a cross arm on said crank shaft for manually rocking it to restore the parts to normal position.

In testimony whereof I have signed this 55 specification.

EDGAR J. WOOD.
